[57] **CLAIM**

The ornamental design for a motorcycle wind sock, as shown and described.

DESCRIPTION

FIG. 1 is a perspective view of the first embodiment of a motorcycle wind sock showing my new design;

1 Claim, 8 Drawing Sheets

FIG. 2 is a left side elevational view thereof, the opposite side being a mirror image;

FIG. 3 is a top plan view thereof;

FIG. 4 is a bottom plan view thereof;

FIG. 5 is a perspective view of the second embodiment of a motorcycle wind sock showing my new design;

FIG. 6 is a left side elevational view thereof, the opposite side being a mirror image;

FIG. 7 is a top plan view thereof;

FIG. 8 is a bottom plan view thereof;

FIG. 9 is a perspective view of the third embodiment of a motorcycle wind sock showing my new design;

FIG. 10 is a left side elevational view thereof, the opposite side being a mirror image;

FIG. 11 is a top plan view thereof;

FIG. 12 is a bottom plan view thereof;

FIG. 13 is a perspective view of the fourth embodiment of a motorcycle wind sock showing my new design;

FIG. 14 is a left side elevational view thereof, the opposite side being a mirror image;

FIG. 15 is a top plan view thereof; and,

FIG. 16 is a bottom plan view thereof.
